(57) **CLAIM**

The ornamental design for a dunnage bag air valve adapter, as shown and described.

DESCRIPTION

FIG. 1 is a three-dimensional top perspective view of a dunnage bag air valve adapter in accordance with some embodiments of the present disclosure.

FIG. 2 is a three-dimensional bottom perspective view of a dunnage bag air valve adapter in accordance with some embodiments of the present disclosure.

FIG. 3 is top perspective view of a dunnage bag air valve adapter in accordance with some embodiments of the present disclosure.

FIG. 4 is a bottom perspective view of a dunnage bag air valve adapter in accordance with some embodiments of the present disclosure.

FIG. 5 is a side perspective view of a dunnage bag air valve adapter in accordance with some embodiments of the present disclosure.

FIG. 6 is an additional side perspective view of a dunnage bag air valve adapter in accordance with some embodiments of the present disclosure.

FIG. 7 is an additional side perspective view of a dunnage bag air valve adapter in accordance with some embodiments of the present disclosure.

FIG. 8 is an additional side perspective view of a dunnage bag air valve adapter in accordance with some embodiments of the present disclosure.

FIG. 9 is a three-dimensional top perspective view of a dunnage bag air valve adapter having four legs in accordance with some embodiments of the present disclosure.

FIG. 10 is a three-dimensional bottom perspective view of a dunnage bag air valve adapter having four legs in accordance with some embodiments of the present disclosure.

FIG. 11 is top perspective view of a dunnage bag air valve adapter having four legs in accordance with some embodiments of the present disclosure.

FIG. 12 is a bottom perspective view of a dunnage bag air valve adapter having four legs in accordance with some embodiments of the present disclosure.

FIG. 13 is a side perspective view of a dunnage bag air valve adapter having four legs in accordance with some embodiments of the present disclosure.

(Continued)

FIG. 14 is a three-dimensional top perspective view of a dunnage bag air valve adapter having stepped legs in accordance with some embodiments of the present disclosure.

FIG. 15 is a three-dimensional bottom perspective view of a dunnage bag air valve adapter having stepped legs in accordance with some embodiments of the present disclosure.

FIG. 16 is top perspective view of a dunnage bag air valve adapter having stepped legs in accordance with some embodiments of the present disclosure.

FIG. 17 is a bottom perspective view of a dunnage bag air valve adapter having stepped legs in accordance with some embodiments of the present disclosure.

FIG. 18 is a side perspective view of a dunnage bag air valve adapter having stepped legs in accordance with some embodiments of the present disclosure.

FIG. 19 is an additional side perspective view of a dunnage bag air valve adapter having stepped legs in accordance with some embodiments of the present disclosure.

FIG. 20 is an additional side perspective view of a dunnage bag air valve adapter having stepped legs in accordance with some embodiments of the present disclosure.

FIG. 21 is an additional side perspective view of a dunnage bag air valve adapter having stepped legs in accordance with some embodiments of the present disclosure.

FIG. 22 is a three-dimensional top perspective view of a dunnage bag air valve adapter having four stepped legs in accordance with some embodiments of the present disclosure.

FIG. 23 is a three-dimensional bottom perspective view of a dunnage bag air valve adapter having four stepped legs in accordance with some embodiments of the present disclosure.

FIG. 24 is top perspective view of a dunnage bag air valve adapter having four stepped legs in accordance with some embodiments of the present disclosure.

FIG. 25 is a bottom perspective view of a dunnage bag air valve adapter having four stepped legs in accordance with some embodiments of the present disclosure; and,

FIG. 26 is a side perspective view of a dunnage bag air valve adapter having four stepped legs in accordance with some embodiments of the present disclosure.

The hatching, if any, shown in the drawings represents a surface of the design having a metallic appearance. The broken lines, if any, shown in the drawings illustrate unclaimed features and form no part of the claimed design.
